(57) **CLAIM**

The ornamental design for a veneer ball bat, as shown and described.

DESCRIPTION

The present technology relates to a veneer ball bat having at least two individual veneer laminations constructed from different types of materials.

FIG. 1 is a top view of a veneer ball bat;

FIG. 2 is a bottom view thereof;

FIG. 3 is a left side view thereof;

FIG. 4 is a right side view thereof;

FIG. 5 is a barrel end view of FIG. 1;

FIG. 6 is a handle end view of FIG. 1;

FIG. 7 is a top view of a second embodiment of the bat of FIG. 1;

FIG. 8 is a bottom view of FIG. 7;

FIG. 9 is a left side view of FIG. 7;

FIG. 10 is a right side view of FIG. 7;

FIG. 11 is a barrel end view of FIG. 7;

FIG. 12 is a handle end view of FIG. 7;

FIG. 13 is a left side view of a third embodiment of the bat of FIG. 1;

FIG. 14 is a right side view of FIG. 13;

FIG. 15 is a barrel end view of FIG. 13; and,

FIG. 16 is a handle end view of FIG. 13.
